(57) CLAIM

The ornamental design for a lip clip palette as shown and described.

DESCRIPTION

FIG. 1 is a front perspective view of a lip clip palette showing the new design;

FIG. 2 is a front view of the lip clip palette;

FIG. 3 is a back view of the lip clip palette;

FIG. 4 is a left side view of the lip clip palette;

FIG. 5 is a right side view of the lip clip palette;

FIG. 6 is a top down view of the lip clip palette;

FIG. 7 is a bottom view of the lip clip palette;

FIG. 8 is a front perspective view of the lip clip palette shown in an alternate configuration with a lid closed;

FIG. 9 is a front view thereof;

FIG. 10 is a back view thereof;

FIG. 11 is a right side view thereof;

FIG. 12 is a left side view thereof;

FIG. 13 is a top down view thereof; and,

FIG. 14 is a bottom view thereof.

The broken lines in the drawings depict portions of the lip clip palette that form no part of the claimed design.
